UNITED STATES PATENT OFFICE.

BENJAMIN B. JACKSON, OF CHICAGO, ILLINOIS.

MOTOR-STARTER.

1,289,788.

Specification of Letters Patent.

Patented Dec. 31, 1918.

Application filed May 9, 1916. Serial No. 96,329.

To all whom it may concern:

Be it known that I, BENJAMIN B. JACKSON, citizen of the United States, residing at Chicago, in the county of Cook and State of Illinois, have invented certain new and useful Improvements in Motor-Starters; and I do hereby declare the following to be a full, clear, and exact description of the invention, such as will enable others skilled in the art

10 to which it appertains to make and use the same.

My invention relates to starters for such prime movers as require auxiliary means for bringing them to the speed at which they begin 15 come self-propelling, its general object being to provide a starter in which the energy will be stored by the prime mover itself and which will require no attention whatever after it is once adjusted in operative condition. More particularly, my invention aims to provide an attachment for a non-self-starting prime mover (such as an internal combustion engine or a single phase alternating current motor of the induction 20 type) having energy storage means arranged to produce a rotary torque in an element which may also be oppositely rotated by the prime mover for replenishing the stored energy; to provide simple and automatically 25 controlled means for connecting the said torque-actuated elements for its said starting purpose when the prime mover is at rest, for automatically releasing said element when the prime mover is to be started, for 30 disconnecting and stopping said element when the stored energy has been used for imparting rotation to the rotor of the prime mover, for thereafter oppositely connecting said element to the prime mover and thereby 35 replenishing the stored energy, for disconnecting said element when the desired amount of energy has been stored, and for returning said element to its starting position when the prime mover is being stopped. Further 40

45 objects are to provide simple means for overcoming any imperfect meshing of the teeth of the said torque-actuated element with those of the gears associated therewith, to utilize both the torque stored in the said 50 element and the torque of other rotatable parts for controlling the position of the said element, to provide simple means for adjusting the forces required for moving the said element from one to another of its said 55 positions (that is to say, its motor-accelerating, recharging, motor-running and motor-

stopped or neutral positions), and to provide simple means for utilizing centrifugal action as one of the forces for effecting a transfer of said element from its motor-running to its 60 neutral position. A further object of my invention is to provide simple means whereby the starting attachment may readily be used for starting the prime mover in either direction.

More particularly, my invention aims to provide mechanical means for augmenting the starting torque of an electric motor and for checking the flow of current to such a motor while the latter is being accelerated, 70 thereby enabling an induction motor to be started with a relatively small current; to provide electromagnetic means in circuit with the motor for releasing the mechanical means when the motor is to be started, to 75 utilize the resistance of the said electromagnetic means for checking the flow of current to the motor while the latter is being accelerated; also to provide means for cutting this resistance out of the motor circuit when 80 the starting has been effected, and means for automatically re-inserting this resistance when the motor comes to rest.

Further objects will appear from the following specification and from the accompanying drawings which show my invention as embodied in a starter for an electric motor. In the drawings,

Fig. 1 is a fragmentary side elevation of an electric motor equipped with one embodiment of the starter of my invention.

Fig. 2 is a fragmentary end view of the same.

Fig. 3 is an enlarged section through two of the clutching members associated with 95 the actuating pinion.

Fig. 4 is an enlarged longitudinal section through the pinion and parts adjacent thereto.

Fig. 5 is a fragmentary elevation of the 100 ratchet on the shaft of the pinion.

Fig. 6 is a diagrammatic view of portions of the mechanism showing their positions while the energy storing spring is being wound.

Fig. 7 is a similar view showing the parts during the acceleration of the motor by the starter.

Fig. 8 is a vertical section through Fig. 1 along the line 8—8.

Fig. 9 is a central vertical section through Fig. 2.

110

Fig. 10 is a partially diagrammatic perspective view of the starter mechanism (with the spring and certain other parts removed) taken when the motor is slowing down and with the centrifugal trip tilted to effect the change from the running to the neutral position.

In applying my invention to an alternating current motor, I mount upon a suitable portion of the motor, such as the oil reservoir 25 of the motor 24 in Fig. 1, a forked frame 30 presenting upper and lower arms 40 and 41 extending parallel to the shaft of the motor. The upper of these arms carries a depending electromagnet 1 and a bracket 36 extending below this magnet between the said arms. Interposed between the bracket 36 and the lower arm 41 is a frame 29 which is rotatable on pivots 28, the rotation being effected by means of a handle 27 fast upon the frame 29 and normally interlocked with a latch 34 on the arm 41.

Pivoted upon the frame 29 by means of horizontal pivots 20 is a rocker arm 12 having two projecting arms 33 and 7 which both overhang the shaft of the motor. The free end of the lower arm 33 is connected by a tension spring 16 to a rack 35 on the frame 29, which rack permits of adjusting the spring by moving the adjacent end of the spring from one notch to another. The upper arm 7 has a main portion concentric with the pivots 20 and is equipped near its free end with successive stops, A, B and C arranged in steps and adapted to engage a pin 3 carried by the armature 2 of the electromagnet, which armature is pivoted to the forked frame 30 and continuously pressed downward by a spring 5. Interposed between the frame 29 and the rocker arm 12 are two pivotally connected links 17 and 21, the former of which is bifurcated and affords bearings for a secondary shaft 37 carrying at each end a pinion 15 and a ratchet wheel 14, these pinions being so disposed that one of them will be adapted to mesh with the internal gear 32 on the shaft of the motor at one side and that upon reversing the frame 29 the other pinion will be brought into mesh with the other side of this gear. Connected to the auxiliary shaft 37 is some torque-producing means, such as the spiral spring 13, which spring is connected at its ends respectively to the shaft 37 and to the pivotal connection between the links 17 and 21.

Assuming this spring 13 to be unwound, the tension in spring 16 will rock the arm 12 toward the left (Fig. 6), forcing the pinion 15 into mesh with a winding gear 31 fast upon the shaft of the motor 31. Then upon rotating the motor shaft by hand in a counter-clockwise direction, this gear 31 will drive the pinion 15 and wind up the

driving spring 13, and owing to the links and their connections to the driving spring, the tension on the latter will set up forces F and G (Fig. 6) acting on the system of parts rocking about the pivot 20, these being in addition to the continuously operative force E, force G being the tension produced in the link 21 by resisting the pull of the spring 13 as applied at the juncture of the links 17 and 21. Forces E and F will both tend to rock the arm 12 toward the left, thereby holding the gear and pinion intermeshed, while force G will tend to swing the arm 12 to the right and to carry the pinion out of mesh with the gear. However, these elements are so arranged that the torque produced about the axis 20 by the force G is greater than the oppositely directed effect of the force F. This difference increases as the tension in the winding spring is increased, until force G overbalances the effect of the other two forces and rocks the arm 12 to the right, thereby carrying the pinion 15 out of mesh with the gear 31. When this occurs, the torque of the winding spring would tend to spin the pinion 15 around, but the latter is promptly checked by a pawl 19 (Figs. 2 and 10) meshing with a ratchet wheel 14 which is also carried by the auxiliary shaft 37. The torque upon this auxiliary shaft being thus taken up by the pawl, force F becomes inoperative, hence force G overbalances the opposing tendency all the more and therefore insures a quick and positive movement of the arm 12 toward the right or until stopped by the engagement of the armature pin 3 with the stop C on the upper projecting arm 7.

When thus stopped, the pinion 15 is out of mesh with the gear 31 and likewise out of mesh with an internal gear 32, which latter is carried by the shaft of the motor and in alignment with the gear 31. However, during the slowing down of the motor, the centrifugal trip on the disk 11 will assume the position N (Fig. 1), thereby raising the pivoted arm 4 and lifting the pin 3 clear of the stop C, thus allowing the rocker arm 12 to move until the pin 3 engages the stop B, in which "neutral" position the elements are left when the motor is stopped. Then upon supplying current to the line wires of Fig. 10, the electromagnet 1 raises its armature, releasing the rocking support 12 and allowing the force G (Fig. 6) to pull this rocker arm to the right until checked by the engagement of the pin 3 with the extreme stop A as in Fig. 7. This brings the pinion 15 into full mesh with the internal gear 32, while also causing the pawl end 45 to strike pin 26, thus moving both pawls against the pressure of the springs 18 (Fig. 2) and releasing the pawls from the ratchet wheels, so that the pinion 15 may be freely rotated.

by the spring 13 and may actuate the internal gear 32 for bringing the motor up to speed. This acceleration is immediately aided by a rise of electrical torque according to the amount of current flowing through the motor windings, this being less than the normal operating current of the motor for the reason that the windings of the electromagnet 1 are in series with the motor windings. When the spring-actuated pinion is driving the internal gear as in Fig. 7, this driving creates a force F which cooperates with the force G due to the pull of the spring. These two forces together so far overbalance the opposing effect of the tension spring 16 (which effect E is reduced by the shortening of the effective lever arm between the spring and the pivot 20, as shown by a comparison of Figs. 6 and 7) that the spring 13 can spend substantially its entire force in accelerating the motor. As the motor gains in speed, forces G and F (Fig. 7) decrease until overbalanced by the force E which then moves the rocker arm 12 to the left, bringing the pinion 15 into mesh with the rewinding gear and also moving a contact block 8 into a position in which it bridges the magnet terminals. The magnet being thus short circuited, the full current is supplied to the motor which thereupon winds the spring until the force G (operating as before) moves the pinion to the entirely unmeshed or motor-running position. During both this rewinding stage and the normal operation of the motor, the trip 6 flies out to a position parallel to the motor shaft, thereby clearing the armature arm 3.

When the motor is being stopped and has slowed down to a speed at which the pinion 15 may be safely brought into mesh with the internal gear 32, the centrifugal trip tilts (as at N in Fig. 1) and raises the armature arm, thereby releasing the rocker arm 12 as before described and allowing the said forces to swing the rocker arm until the latter carries the pinion into partial mesh with the internal gear 32, or in other words into the starting position. To enable the pinion to turn exactly into mesh with either gear, I interpose between the pinion and its shaft a clutch including a pair of co-acting cams consisting (in the embodiment of Figs. 3 and 4) of radial corrugations. I also preferably employ two ratchet wheels both fast upon the shaft of the pinion, but with the respective pawls a half tooth apart, so that when one pawl is at the point of dropping into mesh the other is at least in half mesh, thus insuring a certain and substantially instantaneous checking of the secondary shaft at any point.

It will be obvious that by varying the resistance of the magnet windings, the initial current flowing to the motor may be reduced

to any desired fraction of the current required by the motor when in normal operation, or at least may be kept down to this normal amperage. Consequently, my starter will be advantageous wherever it is desirable to avoid objectionable fluctuations on the circuit. It will also be noticed that my starter requires no special winding of the motor, and that it could readily be built as an assembled whole and attached to motors of various styles of makes, thus (for example) permitting a low-current starting for a squirrel-cage or other rugged type of motor without employing special windings, commutators, or the like. However, while I have shown and described the starting appliance of my invention as applied to an induction motor, I do not wish to be limited for its application to this particular prime mover. Neither do I wish to be limited to the particular arrangement or form of the various elements as herein disclosed, it being evident that the same might be varied in many respects without departing from the spirit of my invention.

I claim as my invention:

1. The combination with a primary shaft, of an external and an internal gear both fast thereon, a torque-actuated secondary shaft, a pair of pinions fast upon the secondary shaft, and a carrier for the secondary shaft, the said carrier being movable about an axis intersecting the axis of the primary shaft to interpose the said pinions respectively between the external and internal gear at opposite sides of the primary shaft.

2. Mechanism as per claim 2, in combination with means associated with the carrier for moving the interposed pinion into engagement with the internal gear.

3. Mechanism as per claim 2, in combination with means mounted on the carrier and responsive to the torque of the secondary shaft for bodily moving the secondary shaft with respect to the main shaft.

4. The combination with a primary shaft, of a secondary shaft extending parallel to and bodily movable with respect to the primary shaft, a gear fast on the primary shaft, a pair of pinions fast on the secondary shaft, an energy storing spring associated with the secondary shaft and arranged for storing energy upon the rotation of the latter in one direction, means for shifting the position of the secondary shaft from one side of the primary shaft to the other and for thereby bringing one or the other of the said pinions into operative engagement with the gear and means responsive to the tension of the spring for bodily moving the secondary shaft to annul the said operative engagement.

5. The combination with a shaft and a gear fast thereon, of a pinion adapted to mesh with the gear, a support for the pin-

4
 ion arranged for moving the pinion into or out of its said intermeshing with the gear, means tending to move the support in one direction; and a coiled spring associated with the pinion and so arranged as to be wound by the rotation of the pinion in one direction, and connections whereby the tension of the spring during its winding will move the support in a direction opposite to that first named and against the opposition of the said means.

6. The combination with a shaft, of a gear fast thereon, a pinion adapted to mesh with the gear, a movable support for the pinion, means for moving the support in one direction, and common means for rotating the pinion and moving the support in the opposite direction, and latching means for holding the support in an intermediate position.

20 7. The combination with a shaft, of an external and an internal gear both fast thereon, a torque-actuated secondary shaft, a pinion fast upon the secondary shaft and adapted to mesh with either gear, means responsive to the torque actuating the secondary shaft, said means tending to move the pinion with respect to the gears, and latching means for holding the pinion out of mesh with both gears.

30 8. In a starter for an electric motor, a gear on the shaft of the motor, a pinion meshing with the gear, and movable out of mesh therewith, means associated with the pinion for rotating the same and for moving the same into or out of mesh with the gear, a magnet in the motor circuit, and mechanism controlled by the magnet for limiting the movement of the pinion by the said means.

40 9. The combination with an electric motor, of a torque-actuated secondary shaft bodily movable with respect to the shaft of the motor, interengageable elements carried by the respective shafts; means controlling the position of the secondary shaft, said means including an electromagnet independent of the magnetic circuit of the motor, and common means for bodily moving the secondary shaft and for operatively disconnecting the electromagnet.

50 10. The combination with a shaft, of a gear fast thereon, a torque-actuated secondary shaft, a pair of pinions fast upon the latter, and means supporting the secondary shaft and arranged for bringing the said pinions respectively into mesh with opposite sides of said gear, and means for latching the secondary shaft against rotation when neither pinion is in mesh with said gear.

60 11. The combination with a shaft, of a gear fast thereon, a pinion adapted to mesh with the gear, a movable support for the pinion, means for moving the support in one direction, and common means for rotating the pinion and moving the support in the

opposite direction, and means for affording three different limits to the movement of the support in the last named direction.

12. The combination with a shaft, of a gear fast thereon, a pinion adapted to mesh with the gear, a pivoted support for the pinion, an adjustable spring arranged for rocking the support in one direction about its pivot, and a spiral spring arranged for rotating the pinion and for rocking the support in the opposite direction.

13. The combination with a shaft, of a gear fast thereon, a pinion adapted to mesh with the gear, a movable support for the pinion, means for moving the support in one direction, and common means for rotating the pinion and moving the support in the opposite direction, means for limiting the movement of the support in the first named direction, and spaced means affording a series of stops for limiting the movement of the support in the last named direction.

14. The combination with a rotor of an electric motor, of spring means for aiding the initial acceleration of the rotor, a resistance in circuit with the motor during its acceleration; and means interlocking with the spring means after the latter has operated, for short-circuiting the resistance.

15. In a motor starter, the combination with a main shaft and a secondary shaft, of interengageable elements carried by the respective shafts, a source of power for rotating the main shaft, a separate source of power for rotating the secondary shaft, means tending to move the secondary shaft to bring the said elements into interengagement, and a latch for restraining the said means, said latch being released by the first named source of power.

16. A motor and starter combination as per claim 9, in combination with centrifugal means controlling the means which control the position of the secondary shaft.

17. A motor and starter combination as per claim 14, in combination with centrifugally controlled means for restoring the said short-circuit when the motor comes to rest.

18. The combination with an electric motor, of mechanical means for aiding the initial acceleration of the rotor, means for reducing the voltage of the current supplied to the motor during the said acceleration, and means responsive to the depletion of the stored energy for thereafter annulling said voltage reduction.

19. The combination with an electric motor, of spring means for aiding the initial acceleration of the rotor, a resistance in circuit with the motor during the said acceleration, and relatively interlocking means responsive to the depletion of stored energy for thereafter disconnecting said spring means and short-circuiting said resistance.

20. In a starter for an electric motor, non-electric means for aiding the electromagnetic structure of the motor in imparting speed to the rotor, a detent for keeping the non-electric means from operating, and common means for releasing said detent and reducing the starting current of the motor.
21. In a starter for an electric motor, non-electric means for aiding the electromagnetic structure of the motor in imparting speed to the rotor, a detent for keeping the non-electric means from operating, and means for releasing said detent, said last named means including an electro-magnet having its winding in series with the motor so as to reduce the supply of current to the motor.
22. In a starter for an electric motor, non-electric means for aiding the electromagnetic structure of the motor in imparting speed to the rotor, electromagnetic means controlling the operation of the non-electric means, mechanism for shortcircuiting the electromagnetic means when the rotor attains a given speed, and means for automatically rupturing said shortcircuit when the rotor is stopped, the electromagnetic means being in series with a winding of the motor so as to reduce the motor-actuating current while the said means are not short-circuited.
23. In a motor starter, a main shaft, a secondary shaft, interengageable elements carried respectively by the two shafts, a movable carrier for the secondary shaft and the element carried thereby, and torque-effecting means connected to the secondary shaft, said carrier being adapted to move the interengageable elements through a cycle of relative positions including a motor-starting, energy-storing and neutral positions; said carrier being so disposed as to be moved through its said cycle merely by the action of the said torque-effecting means and by the reaction on the carrier of the interengaged elements.
24. In a starter for a shaft, a secondary shaft, means for imparting rotation to the latter, interengageable elements carried by the two shafts, a ratchet for latching the secondary shaft against rotating in one direction, and ratchet-releasing means actuated jointly by the supply of energy for the first named shaft and by the said rotation-imparting means.

BENJAMIN B. JACKSON.
